UNITED STATES PATENT OFFICE.

HUGH LOGIE ALLAN AND JAMES MOORE, OF BURMAH, BRITISH INDIA, ASSIGNEES TO THE BURMAH OIL COMPANY LIMITED, OF GLASGOW, SCOTLAND, A BRITISH CORPORATION.

WAX SWEATING AND CRYSTALLIZING APPARATUS.

Application filed December 9, 1924, Serial No. 754,807, and in Great Britain August 29, 1924.

This invention relates to an improvement in or modification of the sweating and crystallizing apparatus for paraffin and like wax described and claimed in the specification of our prior United States Patent No. 1,504,923, of August 12th, 1924.

The present invention has for its object to improve and simplify the construction of the apparatus, to avoid the use of inter-cell air pipes for the escape of air in the wax chambers, to improve and simplify the arrangement and location of the charging and discharging pipes by dispensing with the use of separate inter-cell charging and discharging pipes, and to increase the heating and cooling effect throughout the wax compartments. Other objects and advantages will appear from the following description of the drawings accompanying this specification, whereon:

Fig. 1 is a partial vertical section through the apparatus, the cells being shown broken off for simplicity of illustration and the apparatus being shown in a vertical position.

Fig. 2 is a plan view of the apparatus.

Fig. 3 is a fragmentary horizontal cross-section through the apparatus.

Fig. 4 is a detail vertical-sectional view through two adjacent cooling cells.

Fig. 5 is a plan showing the arrangement of a plurality of adjacent coolers or wax sweating apparatus.

Fig. 6 is a plan view showing the arrangement of the gauze floor of each wax compartment.

Fig. 7 is a detail vertical-sectional view of the gauze floor to a larger scale.

Fig. 8 is an elevation of the steam grid in the charging and discharging space.

The apparatus comprises a plurality of closed chambers or wax compartments 17 which are sealed by filling each compartment with wax or wax mixture to the exclusion of air. The wax compartments are separated by superposed and spaced horizontal heating and cooling cells 13 and the wax compartments are surrounded by an outer shell or casing 10.

In the apparatus described in our prior patent specification, the shell 10 was cylindrical and the wax charging and discharging pipes passed through each cell. We prefer however to locate the charging and discharging pipes outside the periphery of the cells

and we therefore provide a vertical chamber 55 15 at one side of the apparatus, this chamber being closed externally by metal cover plates 16 and being open internally to each of the wax compartments 17 so that there is open communication between the chamber 15 and 60 the wax compartments.

The wax sweating plant may comprise a plurality of coolers each consisting of a complete unit similar to that shown in Fig. 1 each unit being tilted slightly from the vertical position shown in Fig. 1 so as to lean over as indicated in Fig. 5, that the centre A of the top cell and the centre B of the bottom cell are both in a vertical plane C-C 65 passing through the centre of the charging 70 chamber 15.

The oil or wax mixture is supplied to the charging chamber 15 through a connection 14 at the bottom thereof. The connection 14 also serves to run off the sweatings during the sweating process.

The wax is supported in each compartment 17 on a perforated raised support 18 of gauze or expanded metal or the like which rests on distance pieces or bars 19 suitably spaced apart and secured to the top plate of each cell 13. As illustrated in Figs. 6 and 7, we prefer to make the perforated support 18 in two halves with a central removable strip 26 mounted on a stiffening bar 27 85 (shown partly withdrawn in Fig. 6). The cells 13 are, for convenience, constructed of plates lap-jointed at 13^a as shown in Figs. 2 and 3.

Each compartment 17 is enclosed by a 90 cylindrical casing or ring 11 which is suspended from the cell 13 immediately above the compartment. The ring 11 is open at the side adjacent the charging chamber 15 and has air holes 20 diametrically opposite the opening 11^a and close to the underside of the upper cell 13 (see Fig. 1). The lower edge of the ring 11 is just clear of the perforated floor 18. It will be apparent that the air holes 20 are formed in the highest 95 part of each wax compartment 17 so that the air displaced during the charging of the compartment with wax escapes into the next upper compartment. A steam pipe 92 (shown in Fig. 1) extends down the outside 100 of the shell 10 close to the air holes 20 in order to ensure by local heating the maintenance of a clear channel between the air

holes 20 and the shell 10 for the escape of the air during the filling operation.

The uppermost compartment 17 has an oil overflow 24 and an air pipe 25, both of which pass through the top cell 13.

The charging chamber 15 is fitted at the top with a steam pipe connection 21 and at the bottom of the chamber 15 there is a steam drain connection 23. The connections 21 and 23 are connected up by unions 43 or similar connections to a grid formed of two or more steam pipes 28 (see Fig. 8). The steam grid 28 serves to heat the chamber 15 and clear the same of solidified wax prior to sweating. The chamber 15 also serves as an observation space, for which purpose it is fitted at intervals with glass or other transparent windows 30. The unions 43 enable the whole grid 28 to be withdrawn to permit of the removal of the central section 26 of gauze or expanded metal.

A plurality of vertical fins 29 are transversely disposed in each compartment 17, each fin 29 being secured to the underside of the next upper cell 13 (such as by welding), so that the heat within the cells 13 passes by conductivity from the lower plate of each cell 13 to the fins 29 suspended therefrom. The compartments 17 are thereby uniformly heated by the fins 29. The cylindrical ring 11 also serves as a heat radiating fin. The cylindrical fin 11 of the top wax compartment 17 is carried by or welded to the transverse fins 29 instead of being suspended directly from the top cell 13.

The intermediate cells 13 are not connected to the outer shell or casing 10, but are supported one above another by means of packing pieces (not shown) inserted during erection of the apparatus between the gauze or expanded metal 18 on the top of one cell 13 and the lower edges of the fins 29 depending from the next higher cell 13. These packing pieces are preferably made separate from the fins 29 in order that regular vertical spacing of the cells 13 may be obtained in spite of unavoidable inaccuracies in the construction of the cells and their dependent fins.

Heating or cooling water is circulated through the cells by way of inlet pipes 34, the water circulating through the cells in a circuitous or sinuous path by the provision of divisions or baffle bars 33 within the cells 13. The inlet pipes 34 are connected to a header 35 and the water leaves the cells by pipes 32 connected to a header 31. The inlet pipes 34 may be fitted with regulating valves 38 and the outlet pipes 32 with thermometer cups 37.

The observation space 15 is made with removable covers or sections 16 for facilitating access to the interior of the apparatus for cleaning purposes or repairs.

During sweating, the wax in the space be-

tween the cylindrical fins 11 and the shell 10 is supported by a perforated lining 36 (Fig. 1) of gauze or expanded metal.

Provision is made at 39 for water connections if required for washing-out the apparatus.

40 are eye-plate fixed to the top plates of the cells for lifting purposes. 41 are transverse stay bolts for the charging chamber 15.

It will be apparent that the charging chamber 15 serves for filling each compartment between the cells with wax or wax mixture, the air in each compartment escaping through the air holes 20. The absence of so the air pipes described in our prior patent also avoids the necessity of admitting air to replace the wax which collects in and must be drained from the air pipes before crystallization commences.

The charging chamber 15 also serves to carry off the sweatings and finished product after having been cleared of solidified wax by passing steam through the steam grid 28.

The use of solid fins 29 instead of hollow fins simplifies the construction of the apparatus and minimizes any inconvenience which might arise from leakages due to a faulty or fractured hollow fin.

The mode of operation of the apparatus is as follows:—Water at a temperature slightly above the melting point of the wax mixture to be treated is admitted through the header 35 to the pipes 34 and circulates through the cells 13, leaving them by way of the pipes 32 and passing into the header 31. The heat of the cells 13 is transmitted to the fins 29 by conduction and these fins uniformly heat up the wax compartments 17. The wax mixture is then supplied through the charging pipe 14 and rises into the chamber 15 and through the opening in each ring 11 into each wax compartment 17. Each wax compartment is thus successively and completely filled and sealed and the displaced air escapes through the air vents 20 into the upper part of the apparatus. When the apparatus is full, the wax mixture will overflow at 24.

The water circulating through the cells is now gradually reduced in temperature and, when the charge has been cooled to the desired temperature, a period of rest may be given to form the wax crystals.

Steam is then admitted to pipe 21 and passes through the grid 28, thereby clearing the chamber 15 of solidified wax. Sweating is then commenced by gradually raising the temperature of the water circulating through the cells 13. Sweating is continued so long as desired and the sweatings run off through the openings in the rings 11 and into the chamber 15, where they are discharged through the pipe 14. Hot air may be admitted through the pipe 25 to replace the

sweatings without chilling the surface of the oil or wax in the wax compartments. When sweating is completed, the wax is finally melted out by circulating hot water or steam 5 through the cells 13, the wax sweated out running away through the openings in the rings 11 into the chamber 15 and out through the pipe 14.

The pipe 14 is fitted with a branch pipe 10 with a valve through which the sweatings are run off into a suitable receptacle, this branch pipe being closed by means of the valve when the mixture is being supplied to the apparatus. To separate the oil from the 15 wax, the sweated wax or finished product is run off through the branch pipe into a separate receptacle after the sweatings have been removed.

Claims:

20 1. Apparatus for crystallizing and sweating paraffin and like wax, comprising an outer shell, upper and lower heating or cooling cells within said shell, a ring within the outer shell and suspended peripherally from 25 the upper cell so as to enclose a space beneath the upper cell, said ring having an inlet opening at one side and an air vent at the opposite side near the top of said ring, and a wax and oil supply chamber connected 30 to and open to the interior of said shell adjacent the inlet opening in said ring.

2. Apparatus for crystallizing and sweating paraffin and like wax, comprising an upper heating or cooling cell, a casing peripherally suspended from said cell to form a 25 wax-containing space beneath said cell, a lower heating or cooling cell upon which said casing is supported, said casing having an inlet opening at one side and an air vent 40 at the opposite side near the top thereof, a shell surrounding said casing, and a vertical wax and oil supply and discharging chamber connected to said shell and opening into the interior thereof adjacent said inlet opening.

45 3. Apparatus for crystallizing and sweating paraffin and like wax, comprising an outer shell, upper and lower heating or cooling cells within said shell, a ring within the outer shell and suspended peripherally from 50 the upper cell so as to enclose a space beneath the upper cell, said ring having an inlet opening at one side and an air vent at the opposite side near the top of said ring, a wax and oil supply chamber connected to 55 and open to the interior of said shell adjacent the inlet opening in said ring, and a reticulated liner situated in the annular space between the shell and ring for supporting wax in the said space.

60 4. Apparatus for crystallizing and sweating paraffin and like wax, comprising a plurality of superposed and spaced heating or cooling cells, a shell surrounding said cells, a ring peripherally depending from each 65 cell within the casing to form a wax com-

partment beneath each cell, a vertical wax and oil supply and discharging chamber alongside of and outside the periphery of said cells, said chamber being attached to said shell and open to the interior of said 70 wax compartments, and an air vent in each of said rings near the top thereof.

5. Apparatus for crystallizing and sweating paraffin and like wax, comprising a plurality of superposed and spaced heating or 75 cooling cells, a shell enclosing said cells, wax compartments between the cells, a vertical wax and oil supply and discharging chamber alongside of and outside the periphery of said cells, said chamber being attached to 80 said shell and open to said wax compartments, air vents at the top of each wax compartment, a grid of steam pipes extending vertically through the said chamber, and a cover plate for said chamber for enabling 85 removal of the grid.

6. Apparatus for crystallizing and sweating paraffin and like wax, comprising a plurality of superposed and spaced heating or 90 cooling cells, a shell surrounding said cells, a ring peripherally depending from each cell within the casing to form a wax compartment beneath each cell, a vertical wax and oil supply and discharging chamber alongside of and outside the periphery of 95 said cells, said chamber being attached to said shell and open to the interior of said wax compartments, an air vent in each of said rings near the top thereof, and a liner of reticulated metal extending from top to 100 bottom of the apparatus between the cells and surrounding shell, to support wax in the space between the cells and shell.

7. Apparatus for crystallizing and sweating paraffin and like wax, comprising a wax-containing compartment, hollow heating or cooling cells above and below said compartment, a wax and oil supply and discharging chamber alongside of said compartment and open to the interior thereof, 105 an air vent at the opposite side of said compartment and a raised perforated wax support in each compartment, said wax support being constructed in two halves with 110 a central removable strip.

8. Apparatus for crystallizing and sweating paraffin and like wax, comprising a plurality of superposed and spaced heating or cooling cells, cylindrical rings enclosing the spaces between said cells to provide enclosed 115 intermediate wax compartments, an air vent for each compartment, a wax and oil supply and discharging chamber alongside of and outside the periphery of said compartments and open to the interior of said compartments and a raised perforated wax support in each compartment, each wax support being constructed in two halves with a central removable strip.

9. Apparatus for crystallizing and sweat- 120

ing paraffin and like wax, comprising a plurality of superposed and spaced heating or cooling cells, a casing enclosing said cells, a cylindrical ring depending from each cell to provide intermediate wax compartments, a raised perforated wax support in each compartment, each ring resting upon the next lower perforated wax support, a vertical wax and oil supply and discharging chamber alongside of and outside the periphery

of said cells and open to the interior of said compartments, each of said rings having an opening adjacent the charging chamber and an air vent diametrically opposite the opening and close to the underside of the next higher cell.

The foregoing specification signed at Rangoon, this twenty first day of October, 1924.

HUGH LOGIE ALLAN.

JAMES MOORE.
